KARL KELLER, OF ARBON, SWITZERLAND.

CUTTING-MACHINE FOR EMBROIDERY.

1,153,498.

Specification of Letters Patent. Patented Sept. 14, 1915.

Application filed February 17, 1915. Serial No. 8,813.

To all whom it may concern:

Be it known that I, KARL KELLER, a citizen of the Swiss Republic, and resident of Arbon, Switzerland, have invented new and useful Improvements in Cutting-Machines for Embroidery, of which the following is a full, clear, and exact specification.

The present invention relates to certain improvements in cutting-machines for embroidery, that is to an improved machine for cutting the non-embroidered portion from fabrics having longitudinal embroidery thereon, said improvements being particularly described in the following specification with reference to the accompanying drawings in which:

Figure 1 is a vertical transverse section through the middle part of the improved machine taken on the line A—B of Fig. 5 and seen in the direction of the arrow *c*; Fig. 2 is a corresponding partial plan view with a part represented in horizontal section; Fig. 3 is a side elevation of the machine, seen in the direction of the arrow *d* (Fig. 5); Fig. 4 is partly a plan view, partly a horizontal section corresponding to Fig. 3 and shows the drive mechanism of the machine; Fig. 5 is a vertical longitudinal section of the machine taken along the line E—F of Fig. 1; Figs. 6, 7 and 8 show certain protecting attachments of the machine on a larger scale; Fig. 9 is a side elevation on a larger scale of the cutting mechanism of the machine; Fig. 10 is a corresponding transverse section on the line G—H of Fig. 9, seen in the direction of the arrow *i*; Fig. 11 represents on a larger scale a detail part of Fig. 9 in transverse section taken on the line K—L of Fig. 9.

In Figs. 1, 3 and 5 of the drawings, 1 indicates the main frame of the improved machine having two lateral members rigidly connected together. This frame supports the main driving shaft 2 rotatably mounted in bearings 3, 3' (Fig. 5) and actuated by a suitable drive mechanism so as to rotate in the direction of the arrow *m* (Fig. 1). The main shaft 2 carries a number of large wheels or disks 4, 4', 4'' fixed thereon between the frame members and designed to feed or convey the embroidered fabric to be cut. On their periphery the wheels 4, 4', 4'' are provided with a corrugated or rough surface, preferably formed of emery cloth attached thereon or simply of emery stuck thereon, in order to increase the adherence

of the fabric to be conveyed by said wheels. On the machine frame is fixed the forked support 5, the upper arm of which is situated above the conveyer wheels 4, 4', while its lower arm passes between said wheels. The support 5 carries two curved levers 6, 6' pivoted upon the stationary axis 7. Each of these levers is provided at its ends with the rotary rollers 8, 9 or 8', 9', over which pass the endless belts 10 and 11. These belts have a part of their lower section directly overlying the peripheries of the conveyer wheels 4, 4' and are designed to firmly press the fabric down on said wheels in order to insure the frictional feed movement of the fabric under the action of the rotating conveyer wheels.

The front pressure rollers 8, 8' have an eccentric pivotal connection with the levers 6, 6' (Fig. 2) so as to be angularly adjustable on said levers in such a manner that it is possible to vary the center distance between the rollers 8, 9 and 8', 9', which allows of tensioning more or less the pressure belts 10 and 11. By a screw device, the roller pivots can be fixed in their adjusted position. The lever 6 is provided at its front end with a handle 12, by means of which it can be turned upward so as to remove the belt 10 from the conveying wheel 4 in order to facilitate the introduction of the embroidered fabric. On the other hand, the rear lever 6' carries a rod 13 with an adjustable weight 14 which allows of the regulation of the frictional pressure of the pressure belt 11 on the wheel 4'.

The machine frame 1 carries in its upper part a table 15 which serves as a support for the embroidery fabric 16 and has corresponding openings for the passage of the conveyer wheels 4, 4', 4''. It comprises a curved middle part, the curvature of which corresponds to the peripheric surface of said wheels, and two flat end parts somewhat inclined downward to the horizontal line. This table is preferably made of sheet metal, but may also consist of wood. The embroidery fabric 16 is drawn in over the table 15 between the upper peripheric part of the conveyer wheels and the tensioned pressure belts 10, 11 and by the pressure of these belts, which adjust themselves to the periphery of the wheels without any guiding shoes, it is securely seized by the revolving conveyer wheels and conveyed toward the cutting mechanism. This mechanism

consists of a band-like cutter mounted on two rollers, which forms in the well known manner with an oppositely arranged counterpart a parallel narrow slot through which the fabric is drawn for the cutting operation. This mechanism is represented on a larger scale by the Figs. 9, 10 and 11.

The drive mechanism for driving the main shaft 2 is mainly represented in Figs. 3 and 4. In these figures, 17 designates an electric motor actuating through a belt a pulley 19 mounted in the fixed shaft 18. The pulley 19 is rigidly connected with a step pulley 20 connected in its turn by a belt with a greater step pulley 21. The latter is rotatably mounted on the fixed shaft 22 and carries inside an expansion clutch 23 of known construction, by means of which it can be coupled with the small toothed pinion 24 supported on the same shaft 22. To this end, the lengthened nave of the toothed pinion 24 carries a longitudinally movable coupling expander sleeve 25 arranged to be shifted in the one or the opposite direction by means of a forked lever 26 engaging by rollers with a groove of said sleeve. The pinion 24 meshes permanently with the great toothed wheel 27 fastened on the main shaft 2.

The throwing-into or -out of action of the drive mechanism for the main shaft 2 is effected by means of a foot controlled lever 28 shown in Fig. 5, fixed on the shaft 29 supported in the machine frame. The lever 28 carries at its outer end a board like pedal 30 extending over the whole breadth of the machine so that the operation of the drive coupling device can be effected from different points of the machine. On the shaft 29 is keyed the arm 31 connected by a link rod 32 to the forked lever 26. A spring 33 maintains the forked coupling lever 26 in its normal position of engagement, in which the coupling 23 is closed for the operation of the machine.

In order to rapidly stop the rotating conveyer wheels, the forked lever 26 carries a lateral braking shoe 34 which can be brought into contact with a braking rim on the toothed wheel 27 when the coupling 23 is disengaged by means of the pedal 30. At one side of the machine, the main shaft 2 carries a hand wheel 35 by means of which it is possible to also operate the machine by hand when the mechanical drive is thrown out of action.

As already stated above, the cutting tool of the cutting mechanism consists of an endless cutting band 36 passing over the two guide rollers 37, 38 (Figs. 9, 10 and 11). These rollers are rotatably mounted on the upper longer arm of a forked tool carrier 39. The flexible cutting band 36 is fixed with one of its ends to the guide roller 37 and with its other end to the roller 38 and

in the cutting operation it is successively unwound from the first roller and wound upon the roller 38. Between the two guide rollers the cutting band 36 passes at the cutting place with its lower face over an arc-like curved guide-rail 40 bent upward and vertically and adjustably guided by means of a guide-way on the tool carrier 39. The arc-like curved form of this guide-rail corresponds substantially to the periphery of the conveyer wheels 4, 4', so that the cutting edge of the band 36 passes at the cutting place substantially along the same line in which the fabric is drawn by the conveying device through the cutting mechanism. At the inlet and outlet side of the cutting place the guide-rail 40 is provided with curved guide pieces 41, 41' along which the cutting band 36 is guided upward so as to be maintained apart from the curved fabric path $n-o$ where it is out of the cutting place.

The lower arm of the tool carrier 39 supports, opposite to the operative edge of the cutting band, the counter-part 42, rotatably mounted thereon and forming with said cutting edge a parallel narrow slot through which the fabric is drawn during the cutting operation (see also Fig. 10). The width of said slot is adjustable in such a manner as to allow only the non-embroidered fabric to pass, while the embroidered portions are cut along the outline of the projecting embroidery. To this end the counter-part 42 is made in the form of a flap fixed on the movable shaft 43 and is capable of being adjusted in different positions. The device provided for effecting this adjustment consists of an arm 44 fixed on the shaft 43, extending upward over the fabric path $n-o$ and carrying at its free end an adjusting screw 45 provided with a hand wheel. The tool carrier 39 possesses at its rear end an upward directed arm 46 serving as a stop for the adjusting screw 45. Between the arm 46 and the arm 44 is arranged a traction spring 47 which tends to continuously press the adjusting screw 45 against the stop arm 46. The arrangement of this precise adjusting device for the counter-part 42 far above the fabric path $n-o$ has the advantage that the regulating members 44, 45, 46 cannot be soiled or otherwise affected by the dust resulting from the cutting operation. Moreover, owing to the position of the adjusting screw 45 above the fabric path, it is possible to adjust the counter-part 42 also during the operation of the machine, without it being necessary to withdraw the fabric from the cutter, as it was necessary in the hitherto used regulating devices below the fabric path.

Advantageously the cutter 36 occupies at the cutting place an obliquely downward directed position as indicated in Fig. 10. The guide rollers 37, 38 receive then also an

inclined position parallel to the cutter face or they can also, as represented, be arranged vertically with their axis directed horizontally. In this case, however, the guide pieces 5 41, 41' receive a helical form in order that the face of the cutting band 36 may successively pass from the oblique position to the horizontal position. This vertical position of the cutting band guide rollers offers 10 the advantage that the fabric conveying members arranged on both sides near the cutting place, that is the conveying wheels 4, 4' and the pressure belts 10, 11 can be placed as closely as possible to the cutting 15 mechanism, so as to allow of the cutting of narrow embroidered bands.

The cutting mechanism has in the known manner, as seen in plan view, an obliquely directed position with regard to the direction 20 of the feed movement of the fabric (see Fig. 2), which must be varied according to the top projection p of the embroidery to be cut out. To allow of this variation, the tool carrier 39 is pivotally suspended on the vertical pivot 48 in the holder 49 and can be 25 fixed in any desired oblique position by means of the threaded bolt 50 provided with a nut, guided in an elongated slot of the holder 49. The holder 49 is provided with a 30 guide-way and can be adjusted in the vertical direction on the guiding plate 52 by means of an adjusting screw 51 and be fixed in the desired position of height by means of a clamping screw 53. The holder 49 is 35 provided with an elongated slot for the passage of the clamping screw 53.

The guiding plate 52 has on its back side a horizontal pivot 54, by means of which it is pivotally mounted on the stationary support 5 extending over the fabric feed table. Two screws 55, 55', which are guided in curved slots concentrically arranged around the pivot 54 give the possibility of fixing the guiding plate 52 also in the desired angular 40 position on the support 5. On the front side of the guiding plate 52 is adapted the index 45 56 which cooperates with a graduation provided on the support 5 and thus indicates the angular position of the tool carrier on 50 the horizontal axis 54.

The described adjusting device allows the adjustment of the cutting edge of the cutting band 36 and the opposite upper edge of the counterpart 42 with regard to the fabric path $n-o$ in the direction of the height by 55 means of the screw 51 as well as in its angular position by means of the screws 55, 55'. As the fabric is clamped on both sides of the cutting tool by the conveyer wheels 4, 4' and the corresponding pressure belts 10, 11, it can be more or less stretched by the said 60 device transversely to its feed direction, which is advantageous for obtaining a good cutting operation. If this transverse tension of the fabric should for example be

lessened at the rear (right) end of the cutting edge of the tool 36 and raised at the front end thereof, the screws 55, 55' are slightly loosened and the whole tool carrier is somewhat turned around the pivot 54 in 70 the clockwise direction. It results from this manipulation that the tool cutting edge comes on the front side of the machine at a higher level than on the rear side with regard to the periphery of the conveyer wheels 75 4, 4', so that the greater fabric tension will be produced at the front side. An advantage of this regulating device consists also in the fact that all the regulating members are situated above the fabric path $n-o$, so 80 that their manipulation may also be effected during the operation of the machine without it being necessary to remove the fabric from the cutting mechanism.

The cutting and guide roller 37 from 85 which the cutting band is unwound during the cutting operation, is provided with a brake device, while the cutting band guide roller 38 is combined with a convenient driving ratchet device. The brake device is 90 represented by Fig. 11 in section on a larger scale. Against the inner side face of the guide roller 37 is pressed by the spring 58 a brake disk 57 furnished with a lining of leather or the like. The spring 58 bears on 95 the other hand against a plate 59 provided with pins 60, 60' fixed thereon and engaging into holes of the brake disk 57. The bolt or pivot 61 upon which rotates the roller 37 is threaded at both its ends. At the front 100 end the threaded pivot part is flattened on two opposite sides and the plate 59 is slid thereon so as to be prevented from being rotated. A nut 62 screwed upon said pivot part allows of the regulation of the tension 105 of the spring 58, so that the braking action can be varied at will. The braking device has the object to maintain the cutting band under permanent tension during the unwinding as the cutting operation takes place and 110 to cause it to intimately adapt itself to the curved guide face of the guide rail 40. This prevents as well as possible the removal of the cutting band from the guide rail 40 and the variation of its distance from the upper 115 edge of the counterpart 42, which is of great advantage for a good cutting effect.

As the cutting band becomes narrower by sharpening, it must be so arranged that it can be adjusted upon its guide rail 40 with 120 regard to the counterpart 42. This adjustment may for example be effected by means of the adjusting screws 63 (Fig. 10) arranged in any convenient number as regulable stops behind the back face of the cutting band at the cutting place.

In order that the cutting band always runs off from the roller 37 exactly at the same distance from the counterpart 42, the roller 37 is laterally provided with a flange 125

serving as a guide for the back face of the cutting band and is furthermore arranged so as to be capable of being axially displaced with regard to the tool carrier itself. This 5 axial displacement may for example be obtained by the fact that the roller pivot 61 is screwed by its rear threaded end portion into the tool carrier 39, whereon it is secured by means of a counter-nut. In the same 10 way the other guide roller 38 for the cutting band may also be arranged so as to be axially adjustable.

The drive device for the guide roller 38 consists of a worm wheel 64 (Fig. 10) connected with the guide roller 38 and a worm 15 65 engaging with said worm wheel and carrying a ratchet wheel 66. The latter receives an intermittent rotation by means of a pawl lever 68 having a pawl 67 and which 20 is arranged to be oscillated to and fro from the main shaft of the machine. To this end, the main shaft 2 is provided on one side of the machine with a small crank arm 69 (Fig. 5), the active length of which may be 25 varied by means of a set screw 70 passing through a slot in said crank arm. To this crank arm is linked the link rod 71 connected by its upper end to the arm 72 (see also Fig. 3) fixed on the shaft 73. The shaft 73 is rotatably mounted in a tube 74 extending transversely over the fabric feed table, which is supported on the one hand by the upright 75 75 attached to the machine frame and is rigidly held on the other hand by the forked support 5. The shaft 73 passes through the support 5 and carries at its projecting end an arm 76 (Fig. 1) connected by a short link 77 with the above described pawl lever 68 for the intermittent shifting of the cutting 30 band. At each revolution of the machine the described ratchet device has imparted to it a to-and-fro movement which successively carries the cutting band along through the cutting place according to the wear of its 35 cutting edge, whereby the speed of this intermittent cutting band feeding movement can be regulated as required according to the proper wear of the cutting edge. The prolonged worm shaft is also provided with 40 a manually operatable crank 78 (Fig. 9), by means of which the guide roller 38 can also be rotated by hand for manually drawing 45 along the cutting band when required.

The connection of the pawl lever 68 with 50 the actuating arm 76 through the medium of the link 77 is preferably performed with the aid of ball joinings, in order that the lateral adjustability of the tool carrier around the pivot 48 may not be interfered with. 55 Furthermore, the connection of the pawl lever 68 with the link 77 shall be easily releasable, in order that the whole cutting mechanism constituting in some respects one single body can easily be removed from 60 the machine after the disengagement of the 65

screw 53, which is of great advantage for the insertion of a new cutting band.

To obtain a good effect from the cutting mechanism, it is necessary that the fabric enters the cutting mechanism smoothly and 70 without any folds. To this end there is arranged laterally close to the cutting tool on that side from which the fabric approaches the obliquely directed cutting band, a spring acted tensioning lever 79 75 (Figs. 1, 2, 6 and 7) which carries at its front end a pivotally mounted tensioning foot 80 with a concave lower face incurved according to the periphery of the conveyer 80 wheels. The tensioning lever 79 is pivoted on a projection of the roller lever 6 around a pivot 81 and is influenced by a traction spring 82, the action of which may be varied by means of a manually operatable lock lever 83 (Fig. 1). The effect of the tensioning 85 foot 80 is to press down the fabric, which enters the conveying or feeding mechanism without any lateral tension, tightly over the upper edge of the counter-part 42 and to thus stretch it transversely to its feeding 90 movement. This tensioning effect can be varied at will according to the thickness and the stiffness of the fabric, whereby one prevents any formation of folds in the fabric before its entrance into the cutting mechanism, which is very important for the proper 95 cutting operation. Owing to the pivotal arrangement of the tensioning foot 80 on the lever 79, said foot is capable of easily adjusting itself to any unevenness of the fabric. 100

In order to allow of the cutting out of embroideries of different height with one and the same described cutting mechanism, the oblique position of the cutting tool with 105 regard to the direction of the fabric feed movement can be varied by adjustment upon a vertical pivot, as described above. In this case, it is however also necessary to vary the relative distance of the conveying wheels 4, 4' as well as that of the pressure belts 10, 11. 110 The lateral displacement of the conveying wheel 4 can be effected for example by means of the screw spindle 85 movably screwed into said wheel, provided with a hand wheel 86 and held in the wheel 4 so as to be rotatable, 115 but not axially displaceable therein, the wheel 4' being permanently fixed on the shaft 2, while the wheel 4 can be loosened and fastened thereon by means of a set screw 87 having a hand wheel for its operation. In order to allow of the lateral displacement of the pressure belt 10, the roller lever 6 is so arranged on the axis 7 that it 120 can be axially displaced thereon by means of a screw spindle 88 having a hand wheel (Fig. 2), whereby the screw spindle 88 is secured against axial movement by a coupling arm 89 rotatably, but not axially displaceably mounted on the axis 7. As the tensioning lever 79 is supported by a pivot 81 on 125 130

the roller lever 6, it results that when the pressure belt 10 is laterally displaced, the tensioning foot 80 will also simultaneously partake of this lateral displacement. The roller lever 6' with the pressure belt 11 is not displaceable in the lateral direction.

In order that the embroidered fabric to be cut out shall always enter with the embroidered edge at the same part of the cutting tool, there is arranged in front of the conveying device a fabric guiding bar 90 (Figs. 1 and 2) fixed on a vertically adjustable slide 91 guided in a slide-way of the forked support 5. This slide 91 can be adjusted in the direction of the height by means of the adjusting screw 92, while a set screw 93 allows of its fixation in the desired position. The distance of the guiding bar 90 from the table 15 can be regulated at such a degree that it allows only the unembroidered fabric to pass under the bar, while the elevated embroidered edge comes into contact with the bar and is guided by it during the feeding movement of the fabric. On both sides of the fabric guiding bar 90 are placed the rotary rollers 94, 95 and 94', 95' mounted on rocking levers. The rollers, owing to their own weight, are designed to smooth the fabric before its entrance into the conveying device and to prevent as well as possible the formation of folds. This action is still amplified by the fact that the pivots of the said rollers, which latter consist preferably of rubber or any other elastic substance, are not perpendicular, but somewhat inclined to the fabric guiding bar 90, so that the opposite rollers have a somewhat divergent position and tend to laterally spread out the fabric to some extent. On the rear end of the machine is arranged in line with the fabric feeding table a rotary guide roller 96 extending over the whole breadth of the machine and furnished with a rough surface of plush or the like. This roller is actuated by means of a cord pulley 97 (Figs. 1 and 5) fixed on the main shaft 2 and its object is to carry the fabric away from the cutting mechanism by frictional engagement therewith, so as to prevent any gathering of the fabric in the conveying device. Below the guide roller 96 is arranged the folder 97 consisting of a folding board extending over the whole breadth of the machine and carried by a rocking shaft 98. The effect of this folder is to fold the fabric 16 at the rear end of the machine in uniform layers as represented in Fig. 1. The folder is oscillated to and fro by means of a crank arm 99 fixed on the rocking shaft 98 and connected by a link rod 100 to a cord pulley 101. The cord pulley 101 is supported on the upright 75 and is actuated from the cord pulley 102 (Fig. 4) connected to the step pulley 21. In order that behind the cutting mech-

anism the fabric may not be held back or clamped and thus torn by the members of the conveying device, that is the pressure belts 10, 11 with their guide rollers 9, 9' and the conveying wheels 4, 4', there may be provided special protecting attachments for each of the pressure belts 10, 11 and the conveying wheels 4, 4', represented in Figs. 6, 7 and 8; as these protecting attachments are the same for each pressure belt and conveying wheel, it suffices to describe only a single set thereof, for example that for the parts 10 and 4. Upon the pressure belt 10 slides a plow-share-like shoe 103 (Figs. 6 and 7) of sheet metal, pivotally hinged on the lever 6 and is tapered toward the front end (Fig. 7), while it carries at its larger rear end two lateral jaws (Fig. 6) taking over the lateral edges of the pressure belt 10. This protecting shoe prevents the pointed edges of the cut out fabric from being clamped between the pressure belt 10 and the periphery of the guide roller 9, owing to the fact that the lateral jaws of the shoe 103 positively press and direct the fabric downward away from the guide roller. Further, in order that the cut out fabric may not be arrested between the periphery of the conveyer wheel 4, 4' and the corresponding edge of the opening of the table 15, each of said conveyer wheels is provided at its periphery with a circular groove 104, into which engages the middle finger of a three-branch fork 105 of sheet metal (Fig. 8), the side fingers of which take over the lateral edges of the conveyer wheel 4. This protecting fork 105 rests on the fabric feeding table 15 and is pivoted on the pivot 106 in the lateral direction in order that it may follow the conveyer wheel when this is laterally displaced. By the fingers of the protecting fork which slide on the conveyer wheel 4, the fabric is positively detached or removed from the latter and thereby prevented from being clamped in.

The third conveyer wheel 4'' (Fig. 5) assists in parallelly guiding the fabric over its whole breadth through the machine, particularly in the case where fabric pieces of great breadth are to be cut. Above this auxiliary conveyer wheel there is no pressure belt, but the contact of the fabric with said wheel is insured by the rotary roller 107 furnished with a covering of rubber or the like. This roller is carried by a lever 108, which is easily rotatably mounted on the tube 74. It rests by its own weight upon the wheel 4'' to carry the fabric passing between them by frictional engagement through the machine.

The mode of operation of the described machine may be understood without further explanation and the attendance to the machine is limited solely to the application

of the embroidered edge of the fabric longitudinally against the guide bar 90. It is further important to exactly adjust the width of the slot between the cutting band 36 and the counterpart 42 in order that the embroidered edge of the embroidery pattern may be properly cut out.

What I claim is:

1. In a cutting-machine for embroidery, 10 a cutting mechanism, two rotary conveyer wheels, one at each side of said cutting mechanism, provided with a rough surface at their periphery and two corresponding tensioned roller-guided, flexible tractive members arranged above said conveyer wheels and pressed down toward the periphery of the latter so as to hold the fabric on both sides for conveniently feeding it to the cutting mechanism when the conveyer wheels rotate, substantially as described.

2. In a cutting-machine for embroidery, 20 a cutting mechanism, two rotary conveyer wheels, one at each side of said cutting mechanism, provided with a rough surface at their periphery and two corresponding tensioned roller-guided flexible pressure belts arranged above said conveyer wheels and pressed down toward the periphery of the latter so as to hold the fabric on both 30 sides for conveniently feeding it to the cutting mechanism when the conveyer wheels rotate, substantially as described.

3. In a cutting machine for embroidery, a cutting mechanism comprising a cutter and 35 an adjacent counterpart to form between them a slot for the passage of the non-embroidered fabric portion, the cutter consisting of a flexible cutting band fixed on two rollers carried by an adjustable, fixed tool carrier and having controlling means for 40 drawing it successively through the cutting place according to the wear of its cutting edge, substantially as described.

4. In a cutting machine for embroidery, a 45 cutting mechanism comprising a cutter having a concavely curved cutting edge and an adjacent counterpart having a convexly curved operative edge to form a curved slot between said edges for the passage of the 50 non-embroidered fabric portion, substantially as described.

5. In a cutting machine for embroidery, a cutting mechanism comprising a tensioned 55 flexible cutting band and a convex guide piece over which passes said cutting band so as to cause its cutting edge to take a concavely curved form, substantially as described.

6. In a cutting machine for embroidery, a 60 cutting mechanism comprising a tensioned flexible cutting band, two rollers on which said cutting band is fixed, an automatic ratchet device for actuating one of said rollers and a brake device for the other roller 65 so as to obtain an intermittent displacement

of the cutting band in tensioned position, substantially as described.

7. In a cutting machine for embroidery, a cutting mechanism comprising a tensioned flexible cutting band, two rollers on which 70 said cutting band is fixed, an automatic ratchet device for actuating one of said rollers and a brake device for the other roller so as to obtain an intermittent displacement of the cutting band in tensioned position, means 75 being provided to allow also of a manual operation of the first cutting band roller, substantially as described.

8. In a cutting machine for embroidery, a cutting mechanism comprising a tensioned flexible cutting band, rollers for guiding 80 said cutting band and stationary, curved guiding pieces at both ends of the cutting place for directing the cutting band upward apart from the fabric path, substantially as 85 described.

9. In a cutting machine for embroidery, a cutting mechanism comprising a tensioned flexible cutting band having its cutting part 90 obliquely directed downward at the cutting band, substantially as described.

10. In a cutting machine for embroidery, a cutting mechanism comprising a tensioned flexible cutting band having its cutting part 95 obliquely directed downward at the cutting place, rollers for guiding said cutting band and helically curved guiding pieces at both ends of the cutting place for guiding the cutting band from its inclined position to its normal roller guiding, substantially as 100 described.

11. In a cutting machine for embroidery, a cutting mechanism comprising a flexible cutting band, guide-rollers for said cutting 105 band and a carrier for carrying said rollers, one of which is axially displaceable on said carrier for its adjustment according to the breadth of the cutting band, substantially as described.

12. In a cutting machine for embroidery, a cutting mechanism having a stationary support, a cutting tool and a tool carrier, said tool carrier being vertically adjustable on said support and having its adjusting 115 means situated above the fabric path in an easily accessible position, substantially as described.

13. In a cutting machine for embroidery, a cutting mechanism having a stationary 120 support, a cutting tool and a tool carrier, said tool carrier being vertically adjustable on said support and having its adjusting means situated above the fabric path, said tool carrier being also angularly adjustable 125 around a horizontal axis and means being provided above the fabric path for allowing of this angular adjustment, substantially as described.

14. In a cutting machine for embroidery, 130

a cutting mechanism having a cutting tool and a counterpart placed apart from said tool so as to leave free a slot for the passage of the non-embroidered fabric portion, said 5 counterpart being movably supported and provided with regulating means situate above the fabric path for acting upon said counterpart so as to vary its distance from the cutting tool and thereby the width of 10 said slot, substantially as described.

15. In a cutting machine for embroidery, a cutting mechanism comprising a cutting tool and a coöperating counterpart, a conveyer device for feeding the fabric to said cutting mechanism, and a spring acted tensioning member on the inlet side of the cutting mechanism, arranged so as to press down the fabric over the said counterpart of the cutting mechanism and to thus 20 produce a transverse stretching of the fabric, substantially as described.

16. In a cutting machine for embroidery, a cutting mechanism comprising a cutting tool and a coöperating counterpart, a conveyer device for feeding the fabric to said cutting mechanism, and a spring acted tensioning member on the inlet side of the cutting mechanism, provided with a movably hinged tensioning pad and arranged so as 30 to press down the fabric over the said counterpart of the cutting mechanism and to thus produce a transverse stretching of the fabric, substantially as described.

17. In a cutting machine for embroidery, 35 a cutting mechanism, a conveyer device for feeding the fabric to said cutting mechanism, a guide bar for guiding the fabric along its embroidery edge and smoothing rollers divergently arranged on both sides 40 of said guide bar for effectively smoothing the fabric before its entrance into the conveyer device, substantially as described.

18. In a cutting machine for embroidery, 45 a cutting mechanism, a conveyer device for feeding the fabric to said cutting mechanism and an oscillating folding board arranged at the rear end of the machine to fold the fabric by superposed layers, substantially as described.

50 19. In a cutting machine for embroidery, a cutting mechanism, a conveyer mechanism for feeding the fabric to said cutting mechanism, a main drive for said mechanisms, a clutch for said main drive, a foot board extending over the whole breadth of the 55 machine for disengaging said clutch from any point of the same and a brake device oper-

able by said foot board to rapidly arrest the main drive, substantially as described.

20. In a cutting machine for embroidery, 60 a cutting mechanism, two rotary conveyer wheels, one at each side of said cutting mechanism, provided with a rough surface at their periphery and two corresponding tensioned, roller-guided, flexible pressure 65 belts arranged above said conveyer wheels and pressed down toward the periphery of the latter so as to clamp the fabric on both sides, and a guard shoe for said pressure belts having lateral jaws so arranged as to 70 direct the fabric down from the pressure belts and to prevent it from being clamped between the belts and their guide-rollers, substantially as described.

21. In a cutting machine for embroidery, 75 a cutting mechanism, two rotary conveyer wheels, one at each side of said cutting mechanism, provided with a rough surface at their periphery and two corresponding tensioned, roller-guided, flexible tractive 80 members arranged above said conveyer wheels and pressed down toward the periphery of the latter so as to clamp the fabric on both sides for conveniently feeding it to the cutting mechanism when the conveyer 85 wheels rotate, said conveyer wheels being provided with a groove and combined with a guard member arranged to engage with said groove and to detach the fabric from the conveyer wheels during the operation of 90 the machine, substantially as described.

22. In a cutting machine for embroidery, a cutting mechanism, two rotary conveyer wheels, one at each side of said cutting mechanism, provided with a rough surface 95 at their periphery and two corresponding tensioned, roller-guided, flexible tractive members arranged above said conveyer wheels and pressed down toward the periphery of the latter so as to clamp the fabric on 100 both sides for conveniently feeding it to the cutting mechanism when the conveyer wheels rotate, an auxiliary conveyer wheel with a corresponding pressure roller being provided for subsidiarily and correctly feeding 105 the fabric, substantially as described.

In witness whereof I have hereunto signed my name this 28th day of January 1915, in the presence of two subscribing witnesses.

KARL KELLER.

Witnesses:

FRANK TIMMKE,
EMIL MEILE.
